UNITED STATES PATENT OFFICE.

JOHN L. FAGAN, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

STOCKING FORM.

Application filed July 9, 1927. Serial No. 204,491.

This invention relates to certain improvements in forms on which stockings are dried, and in which the foot section beyond the heel is removable from the body of the 5 form.

The object of the invention is to simplify the construction of the means for attaching the foot section to the body of the form, and to provide means for rigidly securing the 10 parts together.

In the accompanying drawing:

Fig. 1 is a side view of a stocking form illustrating my invention;

Fig. 2 is a view showing the opposite 15 side of the form illustrated in Fig. 1;

Fig. 3 is a plan view of the form shown in Fig. 1;

Fig. 4 is an enlarged sectional view on the line 4—4, Fig. 1, showing the method of 20 attaching the foot section to the body of the form.

Fig. 5 is a fragmentary perspective view of the body portion of the form, with the side plates removed;

Fig. 6 is a detached perspective view of 25 the foot section; and

Fig. 7 is a modification of the invention.

1 is the body of the form, having a heel section 2, and 3 is the foot section, including 30 that part of the foot beyond the heel and the toe.

The section 3 is removable, so that different lengths and shapes of foot sections can be attached to the body portion, in order to 35 dry stockings of different sizes.

These forms must be comparatively flat so as not to interfere with the shape of the stocking, and, therefore, no projections must extend beyond the permanent portion of the 40 form which would interfere with the placing of a stocking on the form or its removal therefrom.

In the body portion 1 is a recess 4, on each side of which are shoulders 5—5, and enclosing this recess are two plates 6 and 7, secured together and to the body portion by rivets 45 8 or other suitable fastenings.

The plate 7 has a tongue 9 forming an integral part of the plate as shown, and this 50 tongue has a projection 10 which extends into transverse openings 11 in the two plates 6 and 7, and through an opening 12 in the foot section.

The foot section has an extension 13 which 55 projects into the recess 4 as clearly shown in

Fig. 1, so that when the parts are in position as in Fig. 1, the projection 10 of the spring tongue will enter the opening 12 and firmly secure the foot section to the body portion.

I preferably make the walls 14—14 of the 60 recess 4 slightly tapered, while the edges of the extension 13 of the foot section are also tapered to correspond, so that when the parts are secured together, there is a neat fit between the parts, the projection on the 65 tongue securing the parts together.

The tongue 9 in this instance is an integral part of one of the plates, and is formed by splitting the plates, but in some instances the tongue may be a separate piece, as shown 70 at 9^a, set in a recess in the plate 7^a, and secured thereto by riveting or welding (see Fig. 7).

By the above construction, a very simple 75 and effective means for attaching the detachable foot section to the stocking form is provided, and one in which the foot section can be readily detached by pushing the projection of the spring tongue out of the opening as shown by dotted lines in Fig. 4, 80 after which the foot section can be readily removed and another substituted for it.

I claim:

1. The combination in a stocking form and a detachable foot section, one of said 85 parts having a recess and the other part having a projection adapted to the recess; and a spring tongue on one of said parts movable laterally relative to the form and adapted to engage the other part. 90

2. The combination in a stocking form in which the foot section is detachable, of a body portion having a recess therein, the foot section having a projection adapted to the recess; and a spring tongue movable 95 laterally relative to the form and arranged to lock the foot section and body portion together.

3. The combination in a stocking form, of a body portion having a recess therein; plates on each side of the recess and enclosing said recess at the sides, one of said plates having a tongue with a projection movable laterally relative to the form, the plates having openings arranged to receive the projection on the tongue; and a foot section having an opening into which the projection extends when the parts are assembled. 105

4. The combination in a stocking form in which the foot section is detachable from 110

the body portion, of a body portion having a recess therein; two plates, one on each side of the body portion and secured thereto, said plates closing the recess at the sides, 5 each plate having transverse openings, the foot section having an extension adapted to the recess and having transverse openings therein aligning with the openings in the body portion; and a tongue having a projection movable laterally relative to the form adapted to extend through the transverse openings in the body portion and foot portion, and securing the parts together.

5. The combination in a stocking form, in 15 which the foot section is detachable from the body portion, of a body portion having a tapered recess therein; plates on each side of the body portion and closing the sides of the recess, one of said plates having a spring 20 tongue with a projection, and the other of

said plates having an opening adapted to receive the projection; and a foot section having a tapered extension corresponding to the taper of the recess and having transverse openings therein aligning with the openings in the plate adapted to receive the projection on the tongue.

6. The combination in a stocking form in which the foot section is detachable from the body portion, of a body portion having a recess therein; two plates, one on each side of the body portion and forming the side walls of the recess, one of said plates having an integral spring tongue, the said tongue being provided with a projection, the foot section having an extension adapted to the recess and an opening to receive the projection on the tongue when the projection of the foot section is in the recess.

JOHN L. FAGAN.
